Specification for Design. Patented Oct. 30, 1917.

Application filed May 31, 1917. Serial No. 172,044. Term of patent 3½ years.

To all whom it may concern:

Be it known that I, **ALEXANDER R. KOCH**, a citizen of the United States, residing at New York, New York county, and State of New York, have invented a certain new, original, and ornamental Design for Lace, of which the following is a specification.

The drawing is a plan view of a piece of lace illustrating my new design.

Said design consists of a lace pattern, as illustrated in the accompanying drawing, wherein the body or "net" of the lace is shown in the lower left hand corner only. The principal figures of the design are illustrated as they appear on a section or piece of

the lace, it being understood that these figures may be multiplied indefinitely in accordance with the length of the piece of lace to be made.

What I claim is:

The design for lace as herein shown and described.

In witness whereof, I have hereunto set my hand and seal at New York, New York, this 3rd day of May, A. D. nineteen hundred and seventeen.

ALEXANDER R. KOCH. [L. S.]
